BED SUPPORTED HOLDER FOR SLIPPERS
AND THE LIKE ARTICLESStella Ehrenreich and Simon Stettner,
New York, N. Y.

Application May 24, 1949, Serial No. 95,036

12 Claims. (Cl. 5—317)

1

This invention relates to bed supported holders for slippers and the like articles.

An object of this invention is to provide a holder of the character described, which may be hung on a side rail of a bed, and which is provided with a tray or compartment that opens to the side of the bed so that slippers or other articles may be placed therein and thereby kept off the floor.

Another object of this invention is to provide a holder of the character described, which may be hung onto the strip attached to the side rail of the bed and which normally supports the bed boards, whereby slippers or other articles may be conveniently supported beneath the bed springs of the bed.

Still a further object of this invention is to provide a device of the character described, which may be adjustable to accommodate bed rails having bed board supporting strips of various sizes.

Still another object of this invention is to provide a strong, rugged and durable holder of the character described, which may be made of sheet metal, synthetic plastic or other material, which shall be relatively inexpensive to manufacture, easy to mount on the rail of a bed, which shall be easy to clean and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which are shown various illustrative embodiments of this invention,

Fig. 1 is a perspective view of a holder embodying the invention;

Fig. 2 is a side elevational view of the holder showing the same mounted on a bed rail and said bed rail being shown in cross-section;

Fig. 3 is a top plan view of the structure shown in Fig. 2;

Fig. 4 is an elevational, transverse cross-sectional view of a holder embodying the invention and illustrating a modified construction;

Fig. 5 is a partial perspective view showing a detail.

Referring now in detail to the drawing, 10 designates a holder embodying the invention. Said holder comprises a tray 11. Said tray comprises a horizontal bottom wall 12 which may be

2

rectangular in shape. Extending upwardly from the bottom wall 12 is a rear wall 13 and parallel side walls 14. The walls 13 and 14 are of equal height. The tray 11 may be made of a single piece of sheet metal, if desired.

Attached to the top of the tray 11 is a member 16 which may likewise be made of a single piece of sheet metal. Member 16 comprises a horizontal rectangular wall 17 contacting the upper edges 14a of the side walls 14. Extending downwardly from the ends of wall 17 are flanges 18 which contact the outer surfaces of the side walls 14 and spot welded or soldered or otherwise attached thereto.

It will be noted that the forward edge of the wall 17 is located rearwardly of the front edges 14b of the side walls 14.

Extending upwardly from the front end of wall 17 is a vertical wall 19. The wall 19 extends beyond the opposite side walls 14 as shown in Fig. 1 of the drawing. Extending forwardly from the upper end of vertical wall 19 is a horizontal wall or step 20 of the same length as the wall 19. Extending upwardly from the forward end of wall 20 is a vertical wall 21 likewise of the same length as walls 19 and 20.

It will be noted that the wall 21 is in a plane disposed rearwardly of the vertical plane passing through the front edges 14b of the side walls 14 and the forward edge 12a of the bottom wall 12.

It will now be understood that slippers or other articles may be placed within the tray 11 to rest on the bottom wall 12.

The holder 10 may be mounted on a side rail 25 of a bed as shown in Fig. 2 of the drawing. The side rail 25 has attached to the inner surface 25a thereof, a longitudinal horizontal strip 26 usually located above the lower edge 25b of the side rail, for supporting a bed spring slat or board 30.

In mounting the holder 10 on the side rail 25, the wall 20 contacts the upper surface of the strip 26. The wall 21 contacts the inner surface 25a of the side rail 25 above the strip 26. The wall 19 may contact the inner surface of the strip 26. The forward ends of the upper edges 14a of the side rails 14 may contact the under edge 25b of the side rail 25. The holder 10 is thus easily hung on the side rail of a bed. One of the boards or slats 30 which supports the bed spring may have one of its ends resting on wall 20 to aid in preventing accidental shifting of the holder 10.

In Figs. 4 and 5 there is shown a holder 10a illustrating a modified construction. The hold-

er 10a comprises a tray 11 similar to the tray 11 shown in Figs. 1, 2 and 3. Attached to the top of the tray 11 is a member 40. Said member 40 comprises a top wall 41 similar to wall 17 and provided with flanges 42 similar to flanges 18 and spot welded or otherwise attached to the outer surfaces of the side walls 14.

Extending upwardly from the front end of the top wall 41 is a vertical wall 43 from which extends forwardly a top wall 44. Extending upwardly from the wall 44 is a vertical wall 45. The ends of wall 43 are cut away at their lower edges where the wall extends beyond the side walls 14. Attached to the ends of member 40 are a pair of channel-shaped brackets 50. Each bracket 50 comprises a top wall 51 contacting the top of and spot welded or otherwise attached to one end of top wall 44. Extending downwardly from wall 51 is a wall 52 spot welded to the outer surface of one end of wall 43.

Extending outwardly from the lower end of wall 52 is a wall 53 formed with an internally screw threaded boss 54 to which is screwed a screw 55 having a pointed upper end.

It will be noted that the strip 26 is received within the channels formed by said members 50. The screws 55 may be turned so that their upper pointed ends impinge on the lower surfaces of the strip 26 thereby firmly clamping or attaching the holder 10a to the strip.

Wall 45 may contact the inner surface 25a of the side rail 25. Wall 44 contacts the upper surface of the strip 26. The holder 10a may be adjusted to fit the strip 26. In some beds the strips 26 are located further above the lower edge 25b than in other side rails. Furthermore, the strips 26 may be of different thickness. The adjustable screws 55 may nevertheless be adjusted to firmly clamp the holder to the strip.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative and not in a limiting sense.

Having thus described our invention, we claim as new and desire to protect by Letters Patent of the United States:

1. A holder of the character described, comprising a tray having a bottom wall, a rear upstanding wall, side upstanding walls, and being open at the front and at the top, a member having a transverse horizontal wall contacting the upper edges of the side walls of the tray and flanges extending downwardly from said transverse wall and attached to said side walls, a vertical wall extending upwardly from the forward end of the transverse wall, a wall extending forwardly from the upper end of said vertical wall, and a wall extending upwardly from the forward end of said last mentioned wall.

2. A holder of the character described, comprising a tray having a bottom wall, a rear upstanding wall, side upstanding walls, and being open at the front and at the top, a member having a transverse horizontal wall contacting the upper edges of the side walls of the tray and flanges extending downwardly from said

transverse wall and attached to said side walls, a vertical wall extending upwardly from the forward end of the transverse wall, a wall extending forwardly from the upper end of said vertical wall, a wall extending upwardly from the forward end of said last mentioned wall, and screw threaded means on said member for gripping the bed board strip of the side rail of a bed.

10 3. A holder of the character described, comprising a tray having a bottom wall, a rear upstanding wall, side upstanding walls, and being open at the front and at the top, a member having a transverse horizontal wall contacting the upper edges of the side walls of the tray and flanges extending downwardly from said transverse wall and attached to said side walls, a vertical wall extending upwardly from the forward end of the transverse wall, a wall extending forwardly from the upper end of said vertical wall, and a wall extending upwardly from the forward end of said last mentioned wall, said upstanding wall of said member being spaced from the front open end of the tray.

15 4. A holder of the character described comprising a tray having a bottom wall, a rear upstanding wall, side upstanding walls, and a member attached to the top of the side walls and adjacent the forward ends thereof and being

20 30 formed with channel means opening to the front and adapted to receive a narrow bed board strip on the inner side of a side rail of a bed, spaced above the lower edge of the rail and on which strip the spring supporting slats are

35 mounted, and clamp means on said channel means for clamping said member to said strip.

5. A holder of the character described comprising a tray having a bottom wall, a rear upstanding wall, side upstanding walls, and a mem-

40 ber attached to the top of the side walls and adjacent the forward ends thereof and being formed with channel means opening to the front and adapted to receive a narrow bed board strip on the inner side of a side rail of a bed, spaced above the lower edge of the rail and on which strip the spring supporting slats are

45 mounted, and clamp means on said channel means for clamping said member to said strip, said side walls extending forwardly of said

50 channel means.

6. A holder of the character described comprising a tray having a bottom wall, a rear upstanding wall, side upstanding walls, and being open at the front, a member having a transverse wall

55 attached to the upper ends of the side walls, a vertical wall extending upwardly from said trans-

verse wall and a wall extending forwardly from the upper end of said vertical wall.

7. A holder of the character described comprising a tray having a bottom wall, a rear upstanding wall, side upstanding walls, and being open at the front, a member having a transverse wall attached to the upper ends of the side walls, a vertical wall extending upwardly from said trans-

60 verse wall and a wall extending forwardly from the upper end of said vertical wall, said side walls

65 extending forwardly beyond said forwardly ex-

70 tending wall.

8. A holder of the character described comprising a tray having a bottom wall, a rear upstanding wall, side upstanding walls, and being open at the front, a member having a transverse horizontal wall attached to said side walls, a vertical wall extending upwardly from the forward end

75 of said transverse wall, a wall extending for-

wardly from the upper end of said vertical wall, flanges extending forwardly from said vertical wall, and spaced below said forwardly extending wall, and screw threaded means on said flanges for gripping the narrow bedboard strip on the inner side of the side rail of a bed and spaced above the lower edge thereof.

9. A holder of the character described comprising a tray having a bottom wall, a rear upstanding wall, side upstanding walls, and being open at the front, a member having a transverse horizontal wall attached to the upper ends of the side walls adjacent the forward ends of said side walls, a vertical wall extending upwardly from said transverse wall, a wall extending forwardly from the upper end of said vertical wall, and means on said member for clamping the narrow bedboard strip on the inner side of the side rail of a bed and spaced above the lower edge thereof.

10. A holder of the character described comprising a tray having a bottom wall, a rear upstanding wall, side upstanding walls, and being open at the front, a member attached to the upper ends of the side walls and comprising a transverse vertical wall extending upwardly above said side walls, and a wall extending forwardly from the upper end of said transverse wall, and said side walls extending forwardly beyond said forwardly extending wall.

11. A holder of the character described comprising a tray having a bottom wall, a rear upstanding wall, side upstanding walls, and being

open at the front, a member attached to the upper ends of the side walls and comprising a transverse vertical wall extending upwardly above said side walls, and a wall extending forwardly from the upper end of said transverse wall, and said side walls extending forwardly beyond said forwardly extending wall, and means on said member to clamp the tray to the narrow bedboard strip on the inner side of the side rail of a bed and spaced above the lower edges thereof.

12. A holder of the character described comprising a tray, said tray being open at its front end, the front end of the tray providing means to engage the underside of a side rail of a bed, means on the tray to engage the inner surface of the narrow bedboard strip on the inner side of said side rail spaced above the lower edge thereof, and means to engage the top of said bedboard strip.
